UNITED STATES PATENT OFFICE.

ROY A. PLUMB, OF DETROIT, MICHIGAN.

COMPOSITE TAPERED SHINGLE MAKING.

1,315,575.

Specification of Letters Patent.

Patented Sept. 9, 1919.

Application filed April 28, 1919. Serial No. 293,294.

To all whom it may concern:

Be it known that I, ROY A. PLUMB, a citizen of the United States, and residing at Detroit, in the county of Wayne and State of Michigan, have invented a new and Improved Composite Tapered Shingle Making, of which the following is a specification.

The present invention relates to the manufacture of tapered shingles from fibrous and cementitious materials, its general object being to provide a thoroughly commercial process of producing such shingles, as well as a highly desirable machine for carrying the process into effect. The need for shingles of the class referred to has long been recognized by architects and engineers, but no method or apparatus has to my knowledge been known or available whereby they might be made rapidly and cheaply, the practical result being that they have never come into use to an appreciable extent.

In accordance with my invention, the material (cement, asbestos fiber, etc.) is properly mixed and fed to a movable belt in a puddle which tapers transversely of the line of movement of said belt, that is, in such manner as to form a sheet thin at one edge and thick at the other to correspond to the taper of the shingles, the consistency of the material preferably being such that it will not flow appreciably, but will, on the other hand, retain its relative position throughout the movement of the belt. While in this condition a considerable portion of the excess water is extracted by suction means and the sheet is then compressed to expel additional water and render it sufficiently compact to permit cutting into proper lengths and removal from the belt to thin metal separators. These separators, each carrying the material for a shingle, are then stacked up so that the thin and thick edges of successive shingles are alternately arranged and overlap each other from end to end; and when the stack has attained a sufficient thickness it is slowly subjected to extremely heavy pressure between the platens of a suitable press, removed from the separators, re-stacked, and left to dry and harden. The differences in thickness and consistency in the various portions of the shingles are thus made compensatory, the final result being a cheap, substantially uniform product of pleasing design and smooth finish, and one possessing proper strength, stiffness, toughness and weight.

Considering the operation in its entirety, the material is therefore subjected to the following steps:

(1st) Complete wet mixing, which may be 60 by beaters or other suitable apparatus;

(2nd) Transfer to a movable belt to form a puddle sheet of transversely tapering cross-section;

(3rd) Subjected to suction while on the 65 belt to remove excess moisture, and compressed substantially uniformly from side to side to consolidate the sheet sufficiently to permit its removal;

(4th) Transferred to separator plates and 70 cut into sections or shingles of the desired width;

(5th) Stacked while on the separator plates in alternately reversed arrangement so that the thin edge of a given shingle is opposite 75 or directly above the thick edge of the next lower shingle, whereby a pile of uniform height throughout is secured;

(6th) Slowly subjected to extremely heavy pressure applied vertically to extrude 80 substantially all of the separable water, in which operation any given portion of a given shingle acts complementary to the immediately adjacent portion of the next.

To assist in understanding this action, it 85 is pointed out that sheets of this material, when subjected to pressure, do not consolidate in proportion to their thickness, that is, the pressure being uniform over the sheet, a greater proportional consolidation is secured at the thicker edge than at the thinner, so that if a given shingle were subjected to uniform pressure throughout the thin edge would be more compact than the thicker. These varying consolidations of 90 any two adjacent shingles are made by steps (5) and (6) to offset or compensate one another so that both shingles are substantially 95 uniformly compact throughout;

(7th) Removed from the separator plates, 100 re-stacked, and left to harden.

The various steps may be performed by widely differing apparatus, one preferred installation being shown for the purpose of more fully explaining the invention, and in 105 order to point out certain subordinate features aside from the process itself.

In the drawings, Figures 1 and 1^a together constitute a side elevation of a preferred installation for carrying out the invention, 110 parts being omitted. Fig. 2 is a view on line 2-2 of Fig. 1. Fig. 3 is an elevation

corresponding to Fig. 1^a, parts being broken away and in section, one stack being in the press and another being in the course of formation. Fig. 4 is a section on line 4—4 of Fig. 5 1. Fig. 5 is a perspective view of the stack support or carriage body. Fig. 6 is a fragmentary section on line 6—6 of Fig. 1, showing the belt gripped in the secondary press. Fig. 7 is a view on line 7—7 of Fig. 1. Fig. 10 8 is a diagrammatic elevational view together showing the relation of the clutch-shifting and suction-breaking means. Fig. 9 is a vertical section showing a preferred type of cutter mechanism.

15 The frame of the machine shown comprises uprights 1 and longitudinal bars 2, 3 and 4, on which are supported end pulleys 5, 6 and intermediate pulleys 7 over which a material carrying belt 8 passes in the direction of the arrow, Fig. 1. The pulley 5 is driven in any suitable way, as by means of the clutch pulley 9, Fig. 8, shafting 9' and gearing 9'', and adjacent the pulley 6 the belt 8 passes beneath a hopper 10 to which a thoroughly beaten or mixed puddle 25 of asbestos or other fiber and cement is delivered through the pipe 11.

This hopper has the gage or smoothing plates 12, 13, 14 each of which is independently adjustable at opposite ends toward and from the belt 8, Fig. 2, so that the puddle is delivered to the belt in a sheet 15 which tapers transversely of the line of movement in accordance with the desired difference in thickness between the butts and points of the shingles. The adjusting means shown, which consists of the bolts 16, nuts 17 and springs 18, provides a proper resilient pressure for the smoothing or gaging operation. 40 By providing a driven pulley 20 driven as by means of the belt 21 and the pulley 22 of the gearing 9 and a supporting belt 23 beneath the hopper and gages, the spreading of the wet mass is facilitated.

45 The loaded belt (which while tight enough to support the puddle is nevertheless of such nature as to allow excess water to be withdrawn through it by suction, being preferably formed of felt or the like), after leaving the spreader device, passes over a suction box or boxes 24 connected by means of the pipes 25 to a suitable suction means, not shown, the application of the suction being broken while the belt is moving, as will be explained later.

The belt thereafter passes by a step-by-step movement between the fixed lower and movable upper platens 31 and 32 of a reciprocating press, preferably of the hydraulic type, the faces 33—34 of which, Fig. 60 6, are arranged at an angle to each other substantially equal to the included angle of the shingles. The lower platen is perforated as indicated at 35 to permit the escape of 65 water.

From the press the belt passes to the pulley 5 where the sheet 15 separates from it by virtue of the stiffness imparted it in the press 31—32, and feeds out onto one of the oiled separator plates 36 which has been placed 70 on a table 37 to receive it. A sufficient length of the sheet to form a shingle of proper width having passed onto the plate, it is cut off by any suitable device, such as the cutter 42, Fig. 9, pivoted at 43 and having associated therewith a gripper 44 to which pressure is yieldingly applied through a bar 45 and spring 46 as the cutter lowers about its pivots 43. One means of actuating the cutter consists in the link 48, the treadle 49 and 80 the counterweight 50.

The plates 36 with the wet shingles 38 thereon are transferred one by one to a suitable carriage body or other support such as the plate 52, Fig. 5, on which they are 85 stacked in completely overlapping alternately reverse order, Fig. 3, so that the thin edge of one shingle is interposed between the thick edges of the adjacent shingles. When the stack has reached the desired height, 90 the support 52 is transferred to a main press 53, as by means of the elevating truck 54 and hauling chain device 55—56, and placed between the platens 57—58 thereof, where it is slowly subjected to extremely high pressure to consolidate the material and further 95 expel the water, after which the carriage stack is removed from the press, the shingles taken off the separators and re-stacked in piles for drying.

100 As indicated above, the movement of the belt 8 is step-by-step, the clutch pulley 9 or its equivalent being manipulated to advance the sheet 15 from time to time into the press 31—32, which is controlled by suitable means, not shown, within reach of the operator.

Simultaneously with the application of power to the belt (which may be controlled by the pedal 60, rocker 61, link 62 and shifter bar 63, pivoted at 64, Fig. 8), the suction in the box 24 is broken by the outward movement, Fig. 7, of the valve 65 away from the air inlet 66. Upon the operator depressing the other pedal 67 of the rocker device, Fig. 8, the clutch pulley is disconnected from the shaft 9' and the suction is re-applied to the belt.

Obviously the actual construction of the machine may be widely different from that shown; I do not, therefore, wish to be limited except as indicated by the subjoined claims.

I claim:—

1. That improvement in the art of manufacturing tapered shingles of cementitious material, which consists in forming the shingles wet, transforming them to thin separator plates, arranging them in a stack in such manner that the thick and thin ends com-

pensate for each other, and subjecting the stack to very high pressure transversely of the planes of the shingles.

2. That improvement in the art of manufacturing tapered shingles of cementitious material, which consists in forming the shingles wet, arranging them in a stack alternately with thin separators and in such manner that the thick and thin ends compensate for each other, subjecting the stack to very high pressure transversely of the planes of the shingles, and permitting the material to harden.

3. That improvement in the art of manufacturing tapered shingles of cementitious material, which consists in forming the shingles wet, arranging them in a stack alternately with thin separator plates with the thick ends of one set of shingles over the thin ends of another or interposed set so that the thick and thin ends compensate for each other, and subjecting the stack to very high pressure transversely of the planes of the shingles.

25 4. That improvement in the art of manufacturing tapered shingles of cementitious material, which consists in forming a wet sheet of the material of transversely tapering cross section, consolidating the material by pressure, cutting off sections from the end of the sheet, placing said sections on separators, arranging them in a stack in alternately reverse completely overlapping order, subjecting the stack to very high pressure

transversely of the planes of the sections, and 35 permitting the sections to dry.

5. That improvement in the art of manufacturing tapered shingles of cementitious material, which consists in forming a wet sheet of said material on a movable belt, said 40 sheet tapering transversely of the belt in accordance with the included angle of the desired shingles, drawing excess water from the sheet by suction, and consolidating it by pressure between two surfaces which diverge 45 from each other by an angle substantially equal to said included angle.

6. That improvement in the art of manufacturing tapered shingles of cementitious material, which consists in forming the shingles wet, arranging them in a stack with separator plates between them and in such manner that the thick and thin ends tend to compensate for each other, subjecting the stack to very high pressure transversely of 55 the planes of the shingles, and thereafter permitting them to dry.

7. That improvement in the art of manufacturing tapered shingles of cementitious material, which consists in forming the shingles wet, arranging them in a stack with thin separator plates between them and in such manner that the thick and thin ends compensate for each other, subjecting the stack to very high pressure transversely of 60 65 the planes of the shingles, and thereafter permitting them to dry.

ROY A. PLUMB.
